ABSTRACT: Improved locking means for the cradle of a coin sorter, which cradle has two arms extending across a coin path defined between two plates, the locking means preferably being in the form of a flat member pivotally mounted near its upper end between said plates and normally occupying a position in which a slot or notch in said flat member engages one of the cradle arms to lock the cradle against rocking movement until such time as a coin of predetermined size seats in the cradle and engages and displaces a lower portion of the member to release the cradle arm from the slot.

COIN SORTER CRADLE LOCK

BACKGROUND OF THE INVENTION

This invention relates to coin sorters and more particularly to improved means for releasably locking the cradles normally provided in coin sorters in use today. Such cradles are adapted to receive and be rocked by a downwardly falling coin of a predetermined size, so as to deposit such a coin on a laterally and downwardly extending runway, coins of a lesser size being allowed to pass freely between the arms of the cradle and to continue to fall downwardly. Thus, separation of coins by size is effected.

In the past it has been found that a coin of lesser size may strike an arm of the cradle with sufficient force to tilt the cradle, with the result that such coin is led into the path intended for the larger coins. For example, a 10-cent piece or "dime" may enter the path intended for 5-cent pieces or "nickels" and finish up in the 5-cent tube of a coin changer associated with the coin sorter. The dispensing mechanism of the coin changer may eventually become jammed when it tries to dispense the dime, since it is dimensioned for dispensing nickels, and this can lead to burning out of the coin changer motor, necessitating a service call plus a new motor. Even if the motor is not burned out, the expense of a service call is still involved. It is obviously desirable, therefore, to prevent accidental diversion of smaller coins into the larger coin path. To this end, attempts have been made to provide locking mechanism for locking the cradle against accidental rocking by lesser size coins. However, none of these mechanisms has proven to be completely satisfactory and one of the main problems facing the designer of cradle locking means is the fact that space is at a premium in present-day coin sorters, particularly in the region of the nickel cradle.

It is an object of the present invention, therefore, to provide means for locking a coin sorter cradle, particularly but not exclusively the nickel cradle, which will be highly efficient and at the same time occupy a minimum of space and not interfere with the normal functioning of the coin sorter.

BRIEF SUMMARY OF THE INVENTION

According to the invention I provide in a coin sorter having a cradle adapted to be rocked from a normal position by a coin of predetermined size, said cradle having two arms extending across a coin path defined by two plates, one of which arms initially moves arcuately upward when the cradle is moved from said normal position, the improvement comprising a locking member movably mounted between said plates, having upper and lower portions and being biassed to a position in which said upper portion thereof overlies said one arm to prevent upward movement thereof except when said lower portion of the locking member is displaced a certain amount by a coin seated in said cradle.

Preferably, said locking member comprises a vertically elongated flat member pivotally mounted at its upper end between said plates by a pivot pin which is secured to one of the plates and passes through the member near one side edge thereof, the lower end of the member having a laterally extending slot defined by said upper and lower portions and open at said one side edge of the member, said lower portion extending beyond the upper portion at said one side edge.

BRIEF DESCRIPTION OF THE DRAWINGS

An embodiment of the invention will now be described, by way of example, with reference to the accompanying drawing, in which:

FIG. 1 is a fragmentary view of a plate of a coin sorter having a cradle and the improved locking means of the present invention mounted thereon;

FIG. 2 is a section on the line II-II of FIG. 1;

FIG. 3 is a view similar to FIG. 1 but showing a coin seated in the cradle and the locking means displaced by said coin to free the cradle; and

FIG. 4 is a fragmentary view of the other side of the plate shown in FIG. 1.

DETAILED DESCRIPTION

A coin sorter has two plates 1 and 2 which between them define a path for coins falling downwardly from an entry chute 3. A cradle 4 is shown mounted on plate 1 and for the purposes of the present description it will be assumed that it is a "nickel" cradle, i.e. that it is adapted to receive and be rocked by nickels while allowing "pennies" and "dimes" to pass freely therethrough. It will be understood, of course, that the invention is not restricted to nickel cradles but applies also to "quarter" cradles, etc.

The cradle 4 comprises a plate 5, pivotally mounted on pin 6 secured to plate 1, a biassing weight 7 and two arms 8 and 9 which extend through slots 10 and 11, respectively, in plate 1, these slots being of arcuate shape to accommodate rocking movement of the cradle. It will be seen that the ends of arms 8 and 9 bridge the coin path to intercept nickels, as shown in FIG. 3. Smaller coins, such as "dimes", pass downwardly between the arms.

The plate 1 has a flange 12 extending towards the plate 2 and a locking member 13 is mounted adjacent said flange on a pivot pin 14 secured to the plate 1 and passing through the locking member at the upper end and near the inner edge thereof, the result being that the locking member is biassed toward the position shown in FIG. 1. The locking member has a laterally extending slot 15 therein between an upper portion 16 and a lower portion 17 of the locking member, the lower portion extending beyond beyond the upper portion. It will be apparent that the upper portion 16, with the cradle and locking member in their normal positions as shown in FIG. 1, will prevent the arm 8 from moving arcuately upward in the slot 10. Thus, even if a dime should bounce on to the arm 9 the cradle will not rock but rather the arm 9 will divert the dime back between the arms and thence downwardly as intended. If the dime initially strikes the locking member and accidentally frees arm 8, the cradle will not rock since it is biassed into the position shown.

A nickel entering the coin path via chute 3 falls on the cradle and a portion thereof, of course, passes between the arms 8 and 9 to engage and displace the lower portion 17 of the locking member to the position shown in FIG. 3. Such displacement is sufficient to displace the upper portion 16 to free the arm 8 therefrom, whereby the cradle is allowed to rock, under the influence of the weight of the nickel, to deposit the nickel N on runway 18 to be guided through the sorter in known manner.

The locking means of the present invention takes up a minimum of space, is inexpensive to manufacture, does not interfere with the normal functioning of the sorter and is highly efficient in operation.

I claim:

1. In a coin sorter having a cradle adapted to be rocked from a normal position by a coin of predetermined size, said cradle having two arms extending across a coin path defined by two plates, one of which arms initially moves arcuately upward when the cradle is moved from said normal position, the improvement comprising a locking member movably mounted between said plates, having upper and lower portions and being biassed to a position in which said upper portion thereof overlies said one arm to prevent upward movement thereof except when said lower portion of the locking member is displaced a certain amount by a coin seated in said cradle.

2. A coin sorter as claimed in claim 1, wherein said locking member comprises a vertically elongated flat member pivotally mounted at its upper end between said plates by a pivot pin which is secured to one of the plates and passes through the member near one side edge thereof, the lower end of the member having a laterally extending slot defined by said upper and lower portions and open at said one side edge of the member, said lower portion extending beyond the upper portion at said one side edge.

3. In a coin sorter having a cradle adapted to be rocked from a normal position by a coin of predetermined size and having two arms extending across a coin path defined between

two plates, one of which arms initially moves arcuately upward when the cradle is moved from said normal position, improved locking means for locking said cradle unless released by a said coin of predetermined size, said locking means comprising a member having a substantially horizontal slot therein, means mounting said member between said two plates for movement parallel to said plates towards and away from that side of said one arm which trails during initial movement of the arm, means biassing said member to a position in which said one arm is seated within said slot with an upper portion of said member above the slot preventing such initial movement of the arm, a lower portion of said member below the slot extending beyond the open end of the slot an amount sufficient to ensure release of the arm when said lower portion is displaced by a said coin of predetermined size seated in the cradle.

4. A coin sorter having two plates defining between them a path for downwardly falling coins, a cradle pivotally mounted on the outside of one of said plates and having two arms extending through slot means in said plate to bridge said path, said arms being spaced apart a predetermined distance

whereby they will engage a coin of a predetermined size and prevent passage of said coin therebetween but will permit coins of a lesser size to pass freely therebetween and continue their downward falling movement, said cradle being biassed to a normal coin-intercepting position and adapted to be rocked by a said coin of predetermined size to a coin-discharging position whereby a said coin will be diverted from its original path, and locking means for locking said cradle against accidental rocking by a said coin of lesser size, said locking means comprising a member pivotally mounted between said plates, normally biassed to a locking position and having a slot therein adapted to receive one of the arms of said cradle when the latter is in its normal position, said arm being the trailing arm when the cradle is moving to said coin-discharging position, said slot being defined by upper and lower portions of said member, said lower portion extending beyond the open end of the slot by an amount sufficient to allow a said coin of predetermined size seated in the cradle to displace said member and release said arm from the slot.
